ABSTRACT

Administration of pharmaceutically acceptable 1-methyl-3-keto-4-phenylquinuclidinium salts is described as a chemotherapeutic method of treating hypertension in hypertensives. Daily doses ranging from 10 mg/kg to 300 mg/kg are effective in producing an antihypertensive effect in the latter.

METHOD OF ANTIHYPERTENSIVE
CHEMOTHERAPY UTILIZING
1-METHYL-3-KETO-4-
PHENYLQUINUCLIDINIUM SALTS

BACKGROUND OF THE INVENTION

1. Field of the Invention

The clinical manifestation of hypertension is an elevated systemic arterial pressure. In some cases of hypertension, therapy can be focused on the correction of primary etiological factors, as in pheochromocytoma or Cushing's disease. In most cases, however, the etiology is obscure, and therapy can be directed only to decreasing the abnormal pressure. A common method of achieving the latter is chemotherapeutic administration of an antihypertensive drug. The disclosed use of pharmaceutically acceptable 1-methyl-3-keto-4-phenylquinuclidinium salts is such a method of chemotherapy.

2. Description of the Prior Art

The prior art relating to chemotherapeutic methods of treating hypertensives is discussed comprehensively in the following references: Nickerson, M., "Antihypertensive Agents and the Drug Therapy of Hypertension," in *The Pharmacological Basis of Therapeutics*, 4th Edition, L. S. Goodman and A. Gilman, Editors, New York, Macmillan, 1970, Chapter 33, pages 728-744; and Nickerson, M., "Drugs Inhibiting Adrenergic Nerves and Structures Innervated by Them, III. Adrenergic Neuron Blocking Agents," *op. cit.*, Chapter 26, pages 570-580.

All known antihypertensive agents produce significant untoward side effects, especially the two mainstay drugs reserpine and guanethidine. Reserpine, a rauwolfia alkaloid, is an adrenergic neuron blocking agent which, in addition to affecting arterial blood pressure, causes untoward side effects referable to the central nervous and gastrointestinal systems. Even at low doses reserpine can produce incidence of nightmares and psychic depression. Reserpine commonly produces increased gastrointestinal tone and motility, gastric hyperacidity, and diarrhea. Extrapyramidal disturbances can accompany high doses.

Guanethidine depresses the function of postganglionic adrenergic nerves. Its action is prolonged and its effects are cumulative over extended periods. Tolerance to the drug is observed in 20 percent of patients under chronic treatment, and higher doses are generally required in these cases. The most important complication in guanethidine therapy is postural hypotension, although the following are frequently observed: exertional weakness, bradycardia, nasal congestion and diarrhea.

The compounds of the present invention, 1-methyl-3-keto-4-phenylquinuclidinium salts, have the following structural formula:

where X is a nontoxic anion. These compounds are not related structurally to known antihypertensive agents,

nor are they related to known adrenergic neuron blocking and norepinephrine depleting agents.

The synthesis of 1-methyl-3-keto-4-phenylquinuclidinium salts is described in *J. Org. Chem.*, 22:1484-1489, at 1487-1488 (1957) by T. D. Perrine. In this publication, preliminary reports are included that 3-keto-4-phenylquinuclidine and 4-phenylquinuclidine exhibit analgesic action, but that the latter is quite toxic. A rather thorough review of 10 quinuclidine chemistry and pharmacology can be found in Mashkowsky et al., *Prog. Drug Res.* 13:293-339 (1969).

The pharmacology of 1-methyl-3-keto-4-phenylquinuclidinium salts per se has not been published.

SUMMARY OF THE INVENTION

One essential feature of this discovery is the antihypertensive effect of pharmaceutically acceptable 1-methyl-3-keto-4-phenylquinuclidinium salts when administered to hypertensive mammals. Another essential feature is the production of adrenergic neuron blockade and norepinephrine depletion at neuroeffector sites by administration of these compounds. Administration of an effective amount, ranging between 10 to 300 mg per day, depending on the severity of the case, is effective in reducing systemic arterial pressure in hypertensives to normal levels. In particular, 1-methyl-3-keto-4-phenylquinuclidinium bromide is especially active as an antihypertensive agent. In comparative tests with guanethidine as a reference, 1-methyl-3-keto-4-phenylquinuclidinium salts exhibit greater efficacy as adrenergic neuron blocking and norepinephrine depleting agents.

Because utilization of pharmaceutically acceptable 1-methyl-3-keto-4-phenylquinuclidinium salts in the disclosed method does not involve the central nervous system and is effective at relatively low doses, the complications arising in therapy with reserpine and guanethidine, respectively, can be avoided.

Dose forms of non-toxic 1-methyl-3-keto-4-phenylquinuclidinium salts can be conveniently prepared by the addition of pharmaceutically acceptable carriers generally used in formulations. Dose forms can be prepared in the solid or liquid state by methods known in the art for oral, intravenous and other methods of administration.

DESCRIPTION OF THE PREFERRED
EMBODIMENTS

EXAMPLE 1

The method of producing adrenergic neuron blockade utilizing 1-methyl-3-keto-4-phenylquinuclidinium bromide was compared in two experimental models with the following reference compounds:

clidinium bromide (Steinbach, U.S. Pat. No. 2,648,667 [1953]); oxylidine (Steinbach, *op. cit.*); 3-(3-dimethylaminopropoxy) quinuclidine dimethoxide (Collins et al., *J. Pharm. Sci.*, 56: 1668 [1967]); and quanethidine.

A. Finkleman's Preparation (*J. Physiol. [Lond.]*, 70:145-157 [1930]). Responses of rabbit ileum preparations to periarterial stimulation were recorded before and every ten minutes after the addition to the tissue chamber of a given concentration of the compound being tested. 1-methyl-3-keto-4-phenylquinuclidinium bromide and guanethidine blocked ileum responses to

periarterial stimulation to 50 percent of control in 14 minutes at a concentration of 1 mcg/ml, while clidinium bromide, 3-benzyloxyquinuclidine hydrochloride and 3-(3-dimethylaminopropoxy)quinuclidine dimethiodide did not impair ileum responses after contact with the preparations for one hour at a concentration of 10 mcg/ml.

B. Nictitating Membrane Model. Nictitating membrane responses to pre- and post-ganglionic sympathetic stimulation (0.2 msec. duration, 10 cycles per sec., and supramaximal voltage for 40 sec.) were recorded from anesthetized cats before and after the intravenous administration of 3.1 mg/kg of the compound to be tested. 1-methyl-3-keto-4-phenylquinuclidinium bromide and guanethidine blocked the nictitating membrane responses to both pre- and post-ganglionic sympathetic stimulation by more than 40 percent; 3-(3-dimethylaminopropoxy)quinuclidine dimethiodide antagonized only the responses to preganglionic stimulation, and clidinium bromide and 3-benzyloxyquinuclidine hydrochloride did not modify nictitating membrane responses to either pre- or post-ganglionic sympathetic stimulation.

EXAMPLE 2

The method of depleting norepinephrine levels utilizing 1-methyl-3-keto-4-phenylquinuclidinium bromide was compared to guanethidine according to the procedure described by Phillips et al. in *J. Pharm. Sci.*, 58:572-574 (1969). Heart norepinephrine levels were determined in albino rats at 8 and 24 hr after intraperitoneal administration of 31 mg/kg of 1-methyl-3-keto-4-phenylquinuclidinium bromide or guanethidine. Norepinephrine levels in relation to those of control animals at 8 and 24 hr after drug administration were respectively: 25 and 53% for the 1-methyl-3-keto-4-quinuclidinium bromide, and 8 and 61% for guanethidine.

EXAMPLE 3

The antihypertensive effect of 1-methyl-3-keto-4-phenylquinuclidinium bromide and guanethidine was assessed in mongrel dogs which were made hypertensives by chronic administration of mecamylamine according to the procedure described by Pardo and Vidrio in *J. Pharmacol. Exp. Ther.* 144:124-130, 1964. Control systolic and diastolic blood pressures were recorded three times per week for a period of four weeks. The dogs were then divided into two groups, one of which received 1-methyl-3-keto-4-phenylquinuclidinium bromide in daily oral doses for 4 weeks, and the other guanethidine. Systolic and diastolic blood pressures were recorded three times per week for another period of 4 weeks after administration of the drugs. Mean blood pressure values obtained during the control period were compared with the mean of recordings obtained during treatment. Table I shows the results obtained. No central nervous system effects were observed in dogs treated with either 1-methyl-3-keto-4-phenylquinuclidinium bromide or guanethidine throughout the experiment.

Table I

	Compound	Daily Dose (mg/kg, p.o.)	Number of dogs	Control Systolic/ Diastolic (mmHg)	Treatment Systolic/ Diastolic (mmHg)
5	1-methyl-3-keto-4-phenyl-quinuclidinium bromide	1.0	2	185/99	155/68
		3.1	2	177/87	141/62
10	Guanethidine	10.0	2	186/97	132/56
		1.0	2	183/97	158/70
		3.1	3	195/105	172/88
		10.0	3	179/92	140/63

EXAMPLE 4

Relaxation of nictitating membranes was assessed in unanesthetized cats under chronic administration of either 1-methyl-3-keto-4-phenylquinuclidinium bromide or guanethidine. Relaxation was evaluated in terms of the percent of the greater eye diameter occupied by the membrane. Photographs of the eyes were taken before and at various times after the daily subcutaneous injection of the compounds at 3.1 mg/kg for 29 days. Six cats were used for each compound. Acute relaxation of nictitating membranes reached a maximum after the fifth injection of the two compounds. The values observed were 39 percent in cats treated with 1-methyl-3-keto-4-phenylquinuclidinium bromide and 28.5 percent in cats receiving guanethidine. The maximal residual effect (nictitating membrane relaxation 24 hr after drug administration) was also observed after the fifth dose for both drugs. Animals receiving 1-methyl-3-keto-4-phenylquinuclidinium bromide showed a maximal relaxation of 38.5 percent, an effect which did not decrease significantly throughout the experiment. Cats treated with guanethidine showed a maximal relaxation of 30 percent, which by the end of the experiment had decreased to 15 percent. No central nervous system effects were observed in any of the two groups of cats throughout the experiment.

EXAMPLE 5

Toxicity of 1-methyl-3-keto-4-phenylquinuclidinium bromide and guanethidine was determined by administration of graduated intraperitoneal doses to mice. The LD₅₀ and 95 percent confidence limit was 243 (202-292) mg/kg for 1-methyl-3-keto-4-phenylquinuclidinium bromide, and 184 (160-212) mg/kg for guanethidine.

What is claimed is:

1. A method of producing an antihypertensive effect in a hypertensive mammal, which comprises administering to said mammal an effective amount of a pharmaceutically acceptable 1-methyl-3-keto-4-phenylquinuclidinium salt.
2. A method as in claim 1 wherein said salt is 1-methyl-3-keto-4-phenylquinuclidinium bromide.
3. A method as in claim 1 wherein said amount ranges from 10 mg/kg to 300 mg/kg per day.
4. A method as in claim 1 which further comprises: administering said salt with a pharmaceutically acceptable carrier.
5. A method as in claim 4 wherein said carrier is a solid.
6. A method as in claim 4 wherein said carrier is a liquid.
7. A method as in claim 1 wherein said salt is administered orally.
8. A method as in claim 1 wherein said salt is administered intravenously.
